United States Patent Office

Des. 182,726
Patented May 6, 1958

182,726

PINAFORE

Bess Kaye, New York, N. Y.

Application November 20, 1957, Serial No. 48,562

Term of patent 7 years

(Cl. D3—26)

Fig. 1.

Fig. 2.

Fig. 1 is a front elevational view of a pinafore, showing my new design; and,

Fig. 2 is a rear elevational view of the same.

I claim:

The ornamental design for a pinafore, substantially as shown.
